[57]

ABSTRACT

A balance for a timepiece in which the cross-sectional shape of the balance rim is fixed so that the cross-sectional area and the perimeter of such area are related and definable in terms of a single common variable. Fixed relationship between this common variable and the mean radius of the balance rim is established by virtue of the initial instantaneous power available to oscillate the balance at the desired initial amplitude and frequency. Thus, for each value of the mean radius there exists not only a corresponding value of the cross-sectional area of the balance rim but also a corresponding value of the perimeter of such area. Optimum balance dimensions are obtained from these corresponding values by selecting that value of mean radius which, for the corresponding value of cross-sectional area of the balance rim, produces a maximum value of moment of inertia for the balance with a decrease in amplitude after 24 hours within predetermined limits.

BALANCE FOR A TIME PIECE

CROSS-REFERENCE TO RELATED APPLICATION

This application is a continuation-in-part of copending application Ser. No. 733,416, filed May 31, 1968, and titled Balance for a Time Piece, now abandoned.

BACKGROUND OF THE INVENTION

In the past, timepiece balances have been constructed, in large part, so as to provide as large a size and consequent moment of inertia as would be allowed within the space available for the balance. The shape of the balance rim has been arbitrary and no correlation has been had between cross-sectional area of the balance rim and mean radius of the rim except as to make each as large as is practically possible. Hand in hand with this has been the tendency to use high density material, particularly for the balance rim, in order to allow the balance to be made smaller while still attaining a large value of moment of inertia. Thus, in the prior art, an increase in density of the balance or of its rim is normally employed to allow a decrease in the mean radius and/or cross-section of the balance rim. In contrast to this, the optimum conditions according to this invention demand that when the density is increased, the mean radius of the balance rim must also be increased.

BRIEF SUMMARY OF THE INVENTION

In the present invention, a relationship is established between the cross-sectional area of the balance rim and the mean radius of the rim from its center of oscillation by fixing the cross-sectional shape of the rim and the physical and dynamic characteristics of the balance.

The related values of mean radius and cross-sectional area of the balance rim are then chosen so as to provide a maximum moment of inertia which, for the instantaneous power available after 24 hours and with the balance in the most unfavorable position (in a vertical plane), will not cause a decrease in oscillatory amplitude which exceeds a predetermined value (preferably 40°).

BRIEF DESCRIPTION OF THE DRAWINGS

FIG. 1 is a graph illustrating a certain relationship in connection with a particular embodiment of the invention;

FIG. 2 is a plan view of a balance wheel according to the present invention;

FIG. 3 is an enlarged view partly in section illustrating certain dimensional details of one embodiment of the invention; and,

FIG. 4 is a view similar to FIG. 3, but illustrating a modified form of the invention.

DETAILED DESCRIPTION OF THE INVENTION

With reference to FIG. 2, a balance wheel is indicated generally by the reference character 10 and will be seen to include a hub 12, spokes 14 and a rim 16, the hub being provided with the conventional pivot shafts 18, 20 as may be seen more clearly in FIG. 3. FIG. 3 illustrates an embodiment of the invention wherein the rim 16 is of square cross-section dimensioned as shown and with the rim exhibiting a mean radius R_m as illustrated. The modification according to FIG. 4 illustrates a rim 16' of circular cross-section.

The dissipation of energy by the oscillator is due to internal friction of the hairspring and to friction forces acting upon the balance. The friction torque due to these latter forces when the pivot axis is horizontal may be expressed by the following equation;

$$C = a + b \phi + c \phi^2 \quad (1)$$

where the first term, a , is a constant term independent of oscillatory speed and proportional to the weight P of the balance rim, the radii r of the pivots for the balance, and the coefficient of friction η acting on such pivots. Thus, $a = \eta P$;

the second term is a viscous damping term due to air friction drag on the oscillating balance and is therefore proportional to the instantaneous angular velocity ϕ of the balance and the surface area S of the balance rim; and,

5 the third term is a quadratic term due to non-linear effects of air friction on the balance rim and arms and which also is proportional to the surface area S .

In Equation (1),

$$a = 2\pi R_m A \rho g \eta r$$

$$b = K_1 R_m^3 p$$

$$c = K_2 R_m^4 p, \text{ where:}$$

R_m is the mean radius of the balance rim

A is the cross-sectional area of the balance rim

ρ is the density of the balance material

g is the acceleration due to gravity

η is the coefficient of friction at the balance pivots

r is the balance pivot radius

p is the dimensional girth of the balance rim cross-section

K_1 and K_2 are constants determined experimentally.

By fixing the terms ρ, η , and r , the above may be reduced as follows:

$$(2) \quad a = K_1 R_m A$$

$$(3) \quad b = K_2 R_m^3 p$$

$$(4) \quad c = K_3 R_m^4 p$$

where K_1, K_2 , and K_3 are constants.

Since the terms A and p are both related to the dimensions of the balance rim cross-section, the three expressions may be expressed in terms of only two variables, R_m and s if the shape of the rim cross-section is fixed and s represents some linear dimension of the rim cross-section. For example, if the rim is of circular cross-section and s is the radius of the section, then $A = \pi s^2$ and $p = 2\pi s$. Similarly, for a square cross-section where s is the length of one side, $A = s^2$ and $p = 4s$. Further, for a rectangular rim cross-section where the ratio of the sides is fixed, i.e., the ratio of the radial thickness s to the height h is fixed, then, $h = ns$, n being constant, $A = ns^2$ and $p = 2s(n+1)$.

40 Thus, if the area A is expressed in the general term $A = C_a s^2$ where the constant C_a depends on the cross-sectional shape of the rim, and the girth p is expressed in the general term $p = C_p s$ where the constant C_p also depends upon the cross-sectional shape of the rim, the expressions (2), (3), and (4) may be rewritten as follows:

$$(5) \quad a = K_1 R_m C_a s^2$$

$$(6) \quad b = K_2 R_m^3 C_p s$$

$$(7) \quad c = K_3 R_m^4 C_p s$$

55 As will be shown below, the instantaneous power required to impart an amplitude ϕ to the balance at a frequency ω is as follows;

$$(8) \quad P = (2/\pi) a \omega \phi + (b/2) \omega^2 \phi^2 + (4/3\pi) c \omega^3 \phi^3$$

By substituting (5), (6), and (7) into (8), there results:

$$(9) \quad P = K_4 R_m C_a S^2 \omega \phi + K_5 R_m^3 C_p S \omega^2 \phi^2 + K_6 R_m^4 C_p S \omega^3 \phi^3$$

$K_4 - K_6$ being constants and C_a and C_p being also constants as established by the cross-sectional shape of the rim, as above.

From (9), with the initial available power (at zero hours) P_0 fixed and the frequency ω_0 as well as the initial amplitude ϕ_0 fixed, a direct relation between R_m and S is established, thus:

$$(10) \quad P_0 = K_4 R_m C_a S^2 \omega_0 \phi_0 + K_5 R_m^3 C_p S \omega_0^2 \phi_0^2 + K_6 R_m^4 C_p S \omega_0^3 \phi_0^3$$

which reduces to:

$$(11) \quad K_7 = K_8 R_m s^2 + K_9 R_m^3 s + K_{10} R_m^4 s;$$

$K_8 - K_{10}$ of course being constants ($K_7 = P_0$).

Equation (11) establishes R_m as a function of s , i.e., $R_m = f(s)$ in which the initial amplitude condition ϕ_0 is satisfied.

75 Equation (11) may be further simplified to the form:

$(K_8 R_m)^2 + (K_9 R_m^3 + K_{10} R_m^4) s - P_o = 0$
 or, $s^2 + ps + q = 0$
 with $p = (K_9 R_m^2 + K_{10} R_m^3)/K_8$
 $q = -P_o/K_8 R_m$
 the solution for which is

$$s = \frac{-p}{2} \pm \sqrt{\frac{p^2}{4} - q}$$

Since s must be > 0

$$s = \frac{p}{2} \sqrt{1 - \frac{4q}{p^2} - 1} \quad (12)$$

which yields a single solution for s as a function of R_m .

Since the moment of inertia I of the balance is equal to the product of its mass m times the square of its mean radius R_m , $I = m R_m^2$, and its mass is equal to $2 \pi R_m \rho A$ where the area $A = C_a s^2$ as before,

$$(13) \quad I = 2\pi R_m^3 C_a s^2 \rho$$

Since C_a and ρ have been fixed,

$$(14) \quad I = K_{11} R_m^3 s^2.$$

Equation (14) establishes the moment of inertia as a function of R_m and s , but since $s = f(R_m)$, see Equation (12), has already been established on the basis of P_o and ϕ_o , the moment of inertia may be expressed directly as a function of either R_m or s alone, i.e., $I = F(R_m) = F(s)$. Consequently, for various values of s and of $f(s)$ yielding the corresponding $F(R_m)$ or $F'(s)$, the moment of inertia I may be calculated versus either s or R_m . In FIG. 1, several of these curves, for different densities of the balance material, are shown corresponding to the following fixed values:

$$K_7 = P_o = 5 \text{ ergs/sec.}$$

$$\phi_o = 254^\circ; \phi_{24} = 215^\circ$$

$$\omega = 5\pi \text{ radians/sec.}$$

the balance rim being of square cross-section so that $A = s^2$ and $p = 4s$.

For each value of I in the curves of FIG. 1, there will be a corresponding different power consumption in the 24-hour period so that, after 24 hours, a different instantaneous power $P_{24} = \beta P_o$ will be available. The values of β are also shown in FIG. 1.

Based upon the energy consumption the instantaneous available power may be derived on the basis of the Airy formula:

$$|\Delta\phi| = \frac{1}{I\omega^2} \int_0^{2\pi} C(\theta) \sin \theta d\theta \quad (15)$$

where $\theta = \omega t$ is the phase angle and $\Delta\phi$ is the loss of amplitude during one period and the initial amplitude is ϕ_o .

By definition, $\phi = \phi_o \cos \theta = \phi_o \cos(\omega t)$ from which

$$d\phi/dt = \dot{\phi} = -\omega \phi_o \sin(\omega t) = -\omega \phi_o \sin \theta$$

From Equation (1),

$$(16) \quad |C(\theta)| = a + b\omega\phi_o |\sin \theta| + c\omega^2\phi_o^2 \sin^2 \theta.$$

Substituting (16) into (15) and calculating the loss of amplitude for a quarter of a period to avoid difficulty with signs:

$$\frac{|\Delta\phi|}{4} = \frac{-1}{I\omega^2} \int_0^{\pi/2} (a + b\omega\phi_o \sin \theta + c\omega^2\phi_o^2 \sin^2 \theta) \sin \theta d\theta =$$

$$\frac{1}{I\omega^2} \left(a + \frac{\pi}{4} b\omega\phi_o + \frac{2}{3} c\omega^2\phi_o^2 \right)$$

from which the logarithmic decrement

$$\delta = \frac{|\Delta\phi|}{\phi_o}$$

may be written:

$$\delta = \frac{|\Delta\phi|}{\phi_o} = \frac{1}{I\omega^2} \left(\frac{4a}{\phi_o} + \pi b\omega + \frac{8}{3} c\omega^2\phi_o^2 \right)$$

From the equation for energy consumption

$$E = \frac{1}{2} I \phi_{max}^2 = \frac{1}{2} I \omega^2 \phi_o^2, \quad dE/d\phi_o = I \omega^2 \phi_o$$

Since instantaneous power

$|P| = |dE/dt| = |dE/d\phi_o| \cdot |d\phi_o/dt|$,
 and $C d\phi_o/dt = \Delta\phi/I = (\omega/2\pi)\Delta\phi_o$,
 5 then

$$|P| = \left| \frac{dE}{d\phi_o} \right| \cdot \left| \frac{d\phi_o}{dt} \right| = \frac{1}{2\pi} I \omega^3 \phi_o |\Delta\phi_o| = \frac{1}{2\pi} I \omega^3 \phi_o^2 \delta =$$

$$\frac{2}{\pi} a \omega \phi_o + \frac{b}{2} \omega^2 \phi_o^2 + \frac{4}{3\pi} c \omega^3 \phi_o^3 \quad (17)$$

Equation (8) of course, will be recognized as the generalized form of Equation (17).

Returning to the discussion of FIG. 1, the β of the main-spring is used as the left-hand cut-off point for the I versus R_m curve and the maximum value of I to the right of this cut-off point yields the most efficient balance dimensions producing a loss of amplitude within the prescribed limits. The term $\beta = P_{24}/P_o$ and, from the considerations given above and from FIG. 1, a mainspring with $\beta = 0.76$ is chosen. If it is desired that the loss of amplitude be smaller, a mainspring with $\beta > 0.76$ may be used.

The metals and alloys which may be used are for instance:

Gold alloy 18 K	density 15
Gold alloy 14 K	density 13.8
Silver and gold alloy	density 11
Tungsten alloy	
Platinum	density 21.5

It is also possible to use sintered materials.

The following table gives, by way of example, the characteristics of some balances of the invention, in particular cases:

	P_o erg/s	P (g/ cm^3)	Fre- quency A/h	ϕ_o	ϕ_{24}	I (mg. cm^2)	$D_{ext.}$ (mm)	$s = h$ (mm)
Man's watch	8	15	18000	254	221	52	12.7	.53
Man's watch	8	15	36000	254	221	10.5	8.5	.45
Lady's watch	5	15	18000	254	221	27	11.4	.42
Lady's watch	5	15	36000	254	221	5.4	7.7	.37

In the above table, the frequency A/h refers to alternances per hour whereas the symbol $D_{ext.}$ refers to the outside diameter of the balance wheel.

What is claimed is:

1. In a timepiece of the type having an energy source providing an initial instantaneous available power P_o , and a balance comprising a hub and a rim oscillated at an initial amplitude ϕ_o and frequency ω by said energy source, the improvement comprising,

said rim being of circular cross-sectional shape so that its cross-sectional area $A = \pi s^2$ and the perimeter $p = 2\pi s$, where s is the radius of the cross-section, the mean radius R_m of said rim from its center of oscillation and said dimension s being of fixed relation to establish said initial amplitude ϕ_o at said frequency ω with said initial power P_o , and the value of R_m and the corresponding value of s being fixed to provide that maximum value of moment of inertia of the balance which depletes the instantaneous power available from said energy source by an amount such that after 24 hours of operation with the balance in the vertical position the instantaneous available power P_{24} imparts an oscillatory amplitude ϕ_{24} to the balance wherein $\phi_o - \phi_{24}$ does not exceed about 40° .

2. A timepiece with a balance-hairspring assembly exhibiting a moment of inertia (I), drive means having an initial instantaneous available power P_o for oscillating said balance at a given frequency and with a given initial amplitude ϕ_o and having after 24 hours of operation an instantaneous available power P_{24} for oscillating said balance at said given frequency and with an amplitude ϕ_{24} , said balance having a rim of fixed cross-sectional shape disposed at an average radius R_m from

its center of oscillation and said average radius R_m and the cross-sectional area (A) of said rim being of fixed relation, said rim having its average radius R_m selected to provide a maximum value of (I) for the instantaneous available powers P_o and P_{24} , the initial amplitude ϕ_o , characterized in that the difference in amplitude $\phi_o - \phi_{24}$ does not exceed about 40°.

3. A timepiece movement comprising in combination a balance-hairspring assembly exhibiting a moment of inertia (I) and drive means having an initial power P_o for oscillating said assembly at a given frequency ω with a given initial amplitude ϕ_o and having after 24 hours of operation an available power P_{24} for oscillating said assembly at said given frequency and at an amplitude ϕ_{24} which is less than P_o , said balance having a rim of fixed cross-sectional shape such that its mean radius R_m from its center of oscillation and its cross-sectional area (A) are functionally related according to

$$P_o = K, R_m C_a S^2 \phi_o + K_2 R_m^3 C_p S \phi_o^2 + K_3 R_m^4 C_p S \phi_o^3$$

where

$$C_a s^2 = A, \text{ the cross-sectional area of said rim}$$

$$C_p s = \text{perimeter of said rim cross-section}$$

s = radial thickness of the rim

K_1, K_2 , and K_3 are constants

P_o and ϕ_o are fixed as given above, and said mean radius R_m being of a value such that said moment of inertia (I) is substantially maximum for said related values of R_m and (A)

10
15

6 which produce amplitudes ϕ_{24} according to the following:

$P_{24} = K, R_m C_a S^2 \phi_{24} + K_2 R_m^3 C_p S \phi_{24}^2 + K_3 R_m^4 C_p S \phi_{24}^3$
characterized in that the difference in amplitudes $\phi_o - \phi_{24}$ does not exceed about 40°.

4. In a time piece of the type having an energy source providing an initial instantaneous available power P_o , and a balance comprising a hub and a rim oscillated at an initial amplitude ϕ_o and a frequency ω by said energy source, the improvement comprising,

said rim being of square cross-sectional shape so that its cross-sectional area $A = s^2$ and the perimeter $p = 4s$ where s is the length of one side of said cross-section, the mean radius R_m of said rim from its center of oscillation and said dimension s being of fixed relation to establish said initial amplitude ϕ_o at said frequency ω with said initial power P_o , and the value of R_m and the corresponding value of s being fixed to provide that maximum value of moment of inertia of the balance which depletes the instantaneous power available from said energy source by an amount such that after 24 hours of operation with the balance in the vertical position the instantaneous available power P_{24} imparts an oscillatory amplitude ϕ_{24} to the balance wherein $\phi_o - \phi_{24}$ does not exceed about 40°.
